UNITED STATES PATENT OFFICE.

ANDREW LEIMI, OF PALO, MINNESOTA.

WINDMILL.

1,413,339.

Specification of Letters Patent. Patented Apr. 18, 1922.

Application filed October 7, 1920. Serial No. 415,428.

To all whom it may concern:

Be it known that I, ANDREW LEIMI, a citizen of Finland, Europe, residing at Palo, in the county of St. Louis and State of Minnesota, have invented certain new and useful Improvements in Windmills, of which the following is a specification.

This invention relates to improvements in wind mills and its chief object is to provide 10 a wind mill of maximum power but of simple construction. Another object is to provide a novel and positive method of feathering the blades. The blades, each comprising a pair of hinged wings, are disposed horizontally 15 and two complete sets of blades may be provided if great power is desired. The invention consists in the combination and arrangement of parts to be hereinafter fully described, pointed out in the appended 20 claims and illustrated in the accompanying drawings which form a part of this application and in which—

Fig. 1 is a plan view of my improved wind mill.

25 Fig. 2 is a side view of the same as the mill appears at rest.

Fig. 3 is an enlarged fragmentary view showing the position of diametrically opposite blades when the mill is in operation.

30 Fig. 4 is a plan view of Fig. 3.

Like reference characters denote corresponding parts throughout the several views.

The reference numeral 1 denotes a framework 35 wherein the vertically disposed rotary shaft 2, formed with the longitudinal groove 2^a, is operatively supported, that is driven by the mill blades; power transmission mechanism of any kind desired may be associated with the shaft 2 to transmit power 40 therefrom to the pump or other mechanism to be operated by the mill. The shaft 2 is provided with a lower set of radial arms 3 and an upper set of radial arms 4. The successive arms of each set are disposed at 45 right angles to each other. Each arm 3 or 4 is provided with a blade comprising a pair of wings 5, 6 and each wing is connected by a hinge 7 to its supporting arm 3 or 4. A spring arm 8 is secured to each radial arm and the upper end of each spring arm is connected by a cord or flexible member 9 to the upper edge of the adjacent wing 5, said cord beyond its point of positive engagement 50 with said wing-edge extending to the perforated end 10, to which it is made fast, of

a post 11 which is carried by each radial arm at a point substantially midway between the wings 5, 6 of each blade.

Made fast to the outer or relatively remote edges of each blade 5, 6 are the cords 12, 13 which extend to and through the perforated ends 10 of posts 11 and are then united to form the cord 14, each cord 14 from a blade 5, 6 extending through a perforation 15 in the shaft 2 to the perforated end 10 of the post 11 of the radial arm diametrically opposite, and from said post end 10 the cord 14 branches out to form other cords 12, 13 which run to wings 5, 6 of the diametrically opposed blade.

The purpose of the cords 9 and spring arm 8 is to yieldingly retain the wings 5 raised or open. The mill is driven by the wind blowing between the pairs of wings of any 75 blade. This tends to spread said wings and causes the radial arms to rotate the shaft 2. Spreading the wings of any blade causes its cords 12, 13 to draw cord 14 and so contract the wings of the blade diametrically opposite which blade is positioned with its back to the wind and thus feather this blade or cause it to partially close and offer slight resistance to the wind until such time as its wings are placed in position to receive the 85 wind between them. The members of any pair of diametrically opposed blades will face the wind alternately and when any given blade is "back-to" the wind its resistance to the same is at the minimum; when 90 that blade is faced to the wind it is expanded thereby and its resistance at the maximum. From each cord 14 a drop cord 16 extends to the shaft 2 where said drop cords are united in the common drop cord 17 which extends 95 through a vertical tube 18 disposed in the longitudinal groove 2^a in the said shaft 2, the lower end of said cord 17 being outside the lower end of the tube 18 in easy reach of the operator who may grasp the same to pull 100 the wings closed when it is desired to retain the mill at rest. The mill is stopped at any time by the use of an ordinary brake (not shown) applied to the shaft 2 and the wings then closed in the manner described.

The mill will be started by an ordinary wind, when the brake is off, as a greater surface is presented to the wind by the blades faced to the wind then by the blades positioned "back-to" the wind.

110 What is claimed is:—

1. In a windmill, a framework, a rotary

grooved shaft arranged therein, a tube disposed in the groove in said shaft, radial arms carried by said shaft, said arms being disposed successively at right angles to each other, wings hinged in pairs to said arms, a spring arm carried by each of said radial arms, a flexible element connecting said spring arm and post with one wing of each pair of wings to yieldingly retain the same in a predetermined position, a second flexible element passing through a perforation in the said grooved shaft and having its ends branched and connected to each wing of each pair of diametrically opposed wings, and a second pair of branches formed from said second flexible element, said second pair of branches being united within the aforesaid tube to form a drop cord.

2. In a windmill, a framework, a rotary grooved shaft arranged therein, a tube disposed in the groove in said shaft, radial arms carried by said shaft, said arms being disposed successively at right angles to each other, wings hinged in pairs to said arms, a spring arm carried by each of said radial arms and extending upwardly therefrom, a

post carried by each of said radial arms and disposed upon the opposite side of said wings with relation to said spring arm, said post having a perforated free end, a flexible element secured to one edge of one wing of each pair of wings and its extremities secured to said spring arm and perforated post to yieldingly retain said wing in a predetermined position, a second flexible element passing through a perforation in the said grooved shaft and having its ends branched and slidably engaging the perforated ends of the aforesaid posts and secured to the wings of each pair of diametrically opposed wings, and a second pair of branches formed from said second flexible element, said second pair of branches being united within the aforesaid tube to form a drop cord.

In testimony that I claim the foregoing as my own I have hereto affixed my signature in the presence of two subscribing witnesses.

ANDREW LEIMI.
